UNITED STATES PATENT OFFICE.

HIRAM PERCY MAXIM, OF HARTFORD, CONNECTICUT, ASSIGNOR TO THE MAXIM SILENCER COMPANY, OF HARTFORD, CONNECTICUT, A CORPORATION OF CONNECTICUT.

SILENCER.

Application filed January 25, 1923. Serial No. 615,434.

The subject of this application for Letters Patent is a silencer for quieting the noises of explosive engines, blowers, air compressors and the like and more particularly the object of the invention is the design of a silencer for employing certain principles of noise reduction in a compact, easily assembled structure of large capacity suitable for use with units of large size.

An important principle employed in my improved silencer is that of subdividing or breaking up the initial sound wave into smaller fragments and successively delivering said smaller portions each with reduced energy into the atmosphere so as to practically eliminate all objectionable noise from the unit being silenced. In the practical embodiment of this principle, attention is also given to the avoidance of objectionable back pressure in the handling of relatively large volumes of exhaust gases (or intake gas) and to this end the invention contemplates the provision in a silencer of a series of annular chambers arranged progressively one within the other and communicating with one another by ports or openings at angularly spaced points around their circumference so as to afford a divided passage of unequal length in each chamber between the successive points of intercommunication. The annular chambers with their communicating ports afford a substantially unrestricted path for the flow of gas and due to their circuitous contour are continually dampening out the energy of the sound wave by reflection in addition to the trapping action on the wave and its subdivision into fragments as will be later more particularly explained.

Another object of the invention is to provide a silencing unit of improved and simplified construction capable of cooperating with duplicate units to afford increased silencing capacity whereby, in a silencer of given dimensions, more or less silencing capacity may be provided by the assembling together of a larger or smaller number of said units.

Further objects of the invention are to provide certain improvements tending to insure strength and rigidity of construction (more particularly in silencers of large sizes such as are required to silence the exhaust noises of large and powerful engines) : to facilitate the economical quantity production

of silencers of large capacity: to render practical the construction of large silencers in which provision is made for varying the capacity thereof; and to provide various other improved features of construction contributing to the production of efficient and reliable silencers at low manufacturing costs.

To the accomplishment of the above and further objects as will hereinafter appear, the invention consists in the features of construction and in the combinations and arrangements of parts which will first be described and then particularly pointed out in the appended claims.

The invention will be explained with reference to the accompanying drawings, in which:—

Fig. 1 is a view, in longitudinal section, of a silencer, constructed in accordance with the present invention and illustrating what is at present considered to be the preferred form thereof;

Fig. 2 is a sectional view taken along the line 2—2 of Fig. 1.

Referring to the drawings, the improved silencer therein shown comprises a cylindrical casing 1, and a series of silencer units 2 which are assembled side-by-side within the casing 1, adjacent one end thereof.

The casing 1 consists of a tubular shell 3 and disk-like end plates 4 and 5, the latter being secured to the shell 3 by means of bolts 6 which extend through marginal portions of the end plates and through out-turned flanges 7 at the opposite ends of said shell. The end plate 4 is centrally apertured to provide an inlet 8 through which the exhaust gases may enter the silencer, and the end plate 5 is centrally apertured to provide an outlet 9, which is of substantially the same diameter as the inlet 8, and through which the exhaust gases are discharged from the silencer. To enable the exhaust pipe from the engine to be connected with the silencer in such a way as to support the latter rigidly, the end plate 4 is provided with a series of bolt holes 10 that are tapped to receive fastening bolts (not shown) which are adapted to extend also through a suitable flange on the exhaust pipe. The end plate 5 at the exhaust end of the silencer is similarly provided with a series of bolt holes 12 to facilitate the attachment to the silencer of an escape pipe (not shown) for convey-

105
110

ing away the exhaust gases. As shown, an alternative inlet aperture 14 is provided in the side of the shell 3 adjacent the end plate 4. When not in use, the inlet 14 is closed by means of a cover plate 15, the latter being secured to the shell by means of bolts 16. In case it is found desirable to make use of the inlet 14, the cover plate 15 is removed therefrom and may then be used to cover the inlet 8.

The silencer units 2 are identical and interchangeable except the unit at the innermost end of the series, the latter differing slightly from the rest as will hereinafter appear. With the exception of the innermost one, each unit 2 comprises an annular plate 18 having a plurality of concentric annular flanges or cylindrical walls 19 projecting perpendicularly from one face thereof in equally spaced-apart relation from the outer to the inner periphery of said plate. The innermost silencer unit has the same arrangement of concentric flanges 19 as the other units, said flanges projecting from a disk like plate 20 which has no axial aperture therein. The plates 18 are somewhat smaller in diameter than the inside of the shell 3. The flanges 19 of each unit, are all of the same width so that the edges at their free extremities lie in the same plane, parallel to the annular plate 18, or disk 20, as the case may be. Each flange 19 is formed with a cut-away portion forming a port or opening 22, for interconnecting the channels at opposite sides of the flange. The ports 22 in alternate flanges 19 are preferably disposed at opposite sides of the axis of the silencer, but those at one side of said axis are offset from the common diametrical plane of the ports at the other side of said axis for a purpose which will be hereinafter explained.

The several silencer units are assembled in coaxial side-by-side relation, as shown in Fig. 1, with the free extremities of the flanges 19 abutting the unflanged faces of the annular plates 18 of the adjacent units, thus closing the open sides of the channels formed between the flanges 19 of the silencer units and converting said channels into a series of concentric annular chambers 23. The assembled units are rigidly and firmly held together by means of tie-bolts 25 which extend axially through the plates 18 at spaced intervals. The tie-bolts 25 also extend through the end plate 5 for the purpose of securing the assembled units 2 to said end plate. Nuts 26 upon the ends of the tie-bolts are tightened against the outer face of the end plate 5 to bind the units firmly together. When the units are assembled, as described, the flanges 19 of the several units are alined axially of the silencer and the outermost flanges are spaced a short distance from the inside of the shell 3, thus provid-

ing an annular passage 27 around the outer peripheries of the silencer units. To assist in supporting the assembled silencer units and to relieve the tie-bolts 25 of bending strains, a plurality of bolts 28 are threaded radially through the shell 3, in such locations that their inner ends engage suitable bearing faces 29 on one of the units 2, preferably upon the innermost unit, as shown. The bolts 28 can be carefully adjusted to bring the axis of the innermost unit 2 into exact coincidence with the axis of the shell 3 and such adjustment may be permanently maintained by suitable lock-nuts 30 on said bolts.

The size of each port 22 which interconnects adjacent annular chambers 23 is preferably at least as large as the cross sectional area of one of the annular chambers; the area of the cross section being taken on a plane passing through the axes of the annular chambers. It is thus seen that the flow of the exhaust gases through the successive annular chambers in each unit is unrestricted, thereby reducing objectionable back pressure to a minimum.

The series of silencer units 2 are arranged adjacent the outlet end of the silencer, thus providing a large expansion chamber 32 at the inlet end of the silencer. From the expansion chamber 32 the gases pass into the narrow annular passage 27 surrounding the silencer units, thence through the annular chambers 23 formed between the flanges 19, thence through the ports 22 in the innermost flanges 19 to the alined spaces or chambers 34 at the centers of the silencer units, and thence through the outlet 9 which registers with the chambers 34. It should be noted, however, that the action of the silencer is practically the same in whichever way the gas flows therethrough and consequently aperture 9 may be employed as the inlet and 10 as the outlet.

As the exhaust gas or other sound wave propagating medium enters the expansion chamber 32 the sound waves expand greatly and as a result the noise energy per unit volume of the gas is greatly reduced. The greater part of the sound waves encounter the flat surface of the disk-like plate 20 of the first silencer unit as they reach the outlet end of the expansion chamber and they are deflected backwardly by this plate and thus trapped within said chamber. Only such of the sound waves as reach the region adjacent the shell 3 (which is opposite the entrance to the annular chamber 27) are enabled to escape from the expansion chamber 32 into said annular chamber. Since the waves expand outwardly from the axial center of the expansion chamber 32, the noise energy per unit volume of the gas is less in the region adjacent the shell 3 than at any part nearer the axis of the chamber 32. Thus it will be seen that the entrance to the

passage 27 is located opposite the zone of greatest noise wave expansion and consequently the chamber 32 is made effective to eliminate a maximum amount of the noise.

5 After reaching the annular passage 27 the sound waves pass, through the port 22 in the outermost flange 19 into the outermost of the series of annular silencing chambers 23. The stream of gas entering said port 22 is 10 divided by the flanges 19 which forms the inner wall of said outermost chamber 23, into two branch streams, as indicated by the arrows *a* in Fig. 2, the branch streams passing around, to the opposite side of the silencer where they are reunited at the port leading into the second chamber 23. As the 15 gas passes into said second chamber it is again divided into two branch streams which flow in opposite directions through the second annular chamber 23 (as indicated by the arrows *b* in Fig. 2) until they meet at the opposite side of the chamber, whereupon the reunited streams find an outlet through the adjacent port 22 into the third annular 20 chamber 23. The stream of gas is thereupon again divided into two branch streams and continues to flow back and forth through the interconnected chambers 23 being alternately divided and reunited until it finally reaches the central chamber 34 from which 25 it escapes through the outlet 9.

As the gases progress through the concentric annular chamber 23, the sound waves tend to travel in straight lines and are repeatedly reflected back and forth so that 30 they are broken up and their sound energy is continuously being reduced in the well-known manner common to many forms of silencers.

40 In accordance with the present invention however, provision is made for further breaking up the sound waves and insuring the substantially complete elimination of noise from the exhaust. To this end the 45 ports 22 at one side of the silencer are offset from the diametrical planes of the alternating ports 22 at the opposite side of the silencer, thus causing the branch portions of a sound wave which occur upon entering one 50 port 22 to each travel a different distance to the next port 22 and thus remain in subdivided form according to the proper angular spacing of the successive ports 22.

The amount of the above mentioned offset 55 of the ports 22 is determined relatively to the wave length of the particular sound waves which are to be silenced and is made such as to insure that when the two branches of each divided stream of sound wave prop- 60 agating medium are reunited, the subdivided sound waves will meet in out of phase relation. This may be accomplished for sound waves of a certain known wave length by arrangement of the ports 22, as illustrated in 65 Fig. 2. Preferably the ports 22 are alter-

nately arranged on alternate sides of the axis of said silencer and the angular spacing between successive ports is made slightly more or less than 180° so as to insure the out-of-phase relation between said subdivided portions of the sound wave. 70

The silencing action provided by this arrangement may be further described as follows. A sound wave entering the port 22 of the outermost annular chamber is there 75 divided, one half going to the right and the other to the left. The half which goes to the left arrives at the next port 22 ahead of that which goes to the right. As each half of the wave reaches the second port 22, a 80 portion thereof tails off through said port and is again subdivided in the same manner. The portions of each wave which do not tail off into the second port continue around and around the circuitous chamber in opposite 85 directions and are thereby trapped therein as sound waves pass through one another without the slightest hindrance. However, each time that which remains of each original half wave passes the port 22, another 90 increment tails off through that port. Every increment that enters the second port goes through the same procedure in the second-stage channel and so on through the series. In this way, progressive subdivision 95 splits the original wave into an immense number of small fragments which finally enter the atmosphere over an extended period. By the time the leaving wavelet has reached the central exit, it is a very small 100 fraction of the original wave, and of course it is followed by countless succeeding fragments, coming out one after another. In addition, the reflections throughout the process effect a further large drop in the 105 noise energy. The final discharge is therefore what amounts to a long, low wave, which is inaudible.

It will be obvious also that the capacity of the silencer will be determined by the 110 number of silencer units 2 employed. Thus a manufacturer is enabled to readily construct a muffler of any required capacity by simply assembling the required number of silencer units within the shell 3 and properly securing them in position. After a 115 silencer of this type has been in use its capacity can be readily changed as may be desired by the removal of silencer units from the series or the addition to the series of 120 more units, it being only necessary to employ bolts 25 of the proper length to accommodate the number of units employed.

It will be seen that the above described 125 silencer is of extremely simple construction and that all the parts thereof may be advantageously formed of metallic castings. The silencer units 2 are of such shape that they may be formed economically, each as 130 an integral casting. The ribs 19, as shown,

may be formed with a slight taper to facilitate the drawing of the casting from the mold.

The invention having been described, what is claimed is:—

5. 1. In a device of the character described, a structure providing a central chamber surrounded by a plurality of annular chambers of different diameters one outside of 10 the other in series, the circumferential wall of each chamber having a radially directed port at one side only thereof opening directly into the adjacent chamber for unobstructed communication between adjacent 15 chambers, said ports for successive chambers being angularly displaced from one another by more or less than 180° so as to provide in each annular chamber a divided 20 passage of unequal length between successive ports.

2. In a device of the character described, a structure providing a central tubular chamber concentrically surrounded by a group of annular chambers, the circumferential wall of each chamber having a radially directed port at one side only thereof opening directly into the adjacent chamber for unobstructed communication between adjacent chambers, said ports for successive 30 chambers being alternately disposed at opposite sides of the axis of said group and angularly displaced from one another by more or less than 180° so as to provide in each annular chamber a divided passage of 35 unequal length between successive ports.

3. In a device of the character described, a structure providing a central chamber surrounded by a plurality of annular chambers of different diameters one outside of the other in series, the radial width of each annular chamber being many times smaller than the circumferential length thereof, the circumferential wall of each chamber having a radially directed port at one side only thereof opening directly into the adjacent chamber for unobstructed communication between adjacent chambers, said ports for successive chambers being angularly displaced from one another by more or less than 180° 45 so as to provide in each annular chamber a divided passage of unequal length between successive ports.

4. In a device of the character described, a structure providing a central chamber surrounded by a plurality of annular chambers of different diameters one outside of the other in series, the circumferential wall of each chamber having a port at one side only thereof for communication between adjacent chambers, the size of each port being at least as large as the cross sectional area of an annular chamber, said ports for successive chambers being angularly displaced from one another by more or less than 180° so as 60 to provide in each annular chamber a di-

vided passage of unequal length between successive ports.

5. In a device of the character described, a structure comprising a plurality of radially spaced and concentrically arranged cylindrical walls with end closures therefor to provide a series of concentric annular chambers, each cylindrical wall having a radially directed port at one side only thereof opening directly into the adjacent chamber for 70 unobstructed communication therewith, the ports in adjacent walls being angularly displaced from one another by more or less than 180° so as to provide in each chamber a divided passage of unequal length between 75 successive ports.

6. In a device of the character described, a structure comprising a plurality of radially spaced and concentrically arranged cylindrical walls with end closures therefor to provide a series of concentric annular chambers, each cylindrical wall having a port at one side only thereof opening directly into the adjacent chamber for unobstructed communication therewith, the size of each port 85 being at least as large as the cross sectional area of an annular chamber, the ports in adjacent walls being angularly displaced from one another by more or less than 180° so as to provide in each chamber a divided 90 passage of unequal length between successive 95 ports.

7. In a device of the character described, a structure comprising a plurality of radially spaced and concentrically arranged cylindrical walls, the innermost wall forming a central, tubular chamber and the outer walls a series of concentric annular chambers, end plate closures for said chambers, each cylindrical wall having a radially directed port 100 at one side only thereof opening directly into the adjacent chamber for unobstructed communication therewith, the ports in adjacent walls being angularly displaced from one another by more or less than 180° so as to 105 provide in each chamber a divided passage of unequal length between successive ports, an enclosing cylindrical casing for said structure arranged to provide an enlarged expansion chamber at one side of said structure, said casing having its cylindrical wall spaced from the wall of the outermost chamber, one of said end plates closures serving as the end of said cylindrical casing and having an aperture opening into said central 110 tubular chamber.

8. In a device of the class described, a cylindrical casing having an inlet at one end and a centrally apertured end plate at its opposite end, a structural unit within said casing comprising a plate having a plurality of annular concentric flanges projecting from one side thereof, the outer flange being spaced from said casing and the free edges of said flanges abutting said end plate with 120 125 130

- the inner flange registering with the aperture therein to provide a series of annular concentric chambers having a common axis, the adjacent flanges having radially directed 5 ports therein arranged alternately at opposite sides of said axis and angularly displaced from one another by more or less than 180° so as to provide in each annular chamber a divided passage of unequal length between successive radially directed ports, said ports opening directly into adjacent chambers for unobstructed communication therethrough.
9. In a device of the class described, a cylindrical casing having an inlet at one end and a centrally apertured end plate at its opposite end, a series of structural units within said casing, each comprising a plate having a plurality of annular concentric 15 flanges projecting from one side thereof, the outer flange of each unit being spaced from said casing and the free edges of the flanges abutting the unflanged face of the adjacent unit to provide a series of annular concentric 20 chambers having a common axis, all of said units except the first being centrally apertured with the apertures formed thereby registering with each other and with the aperture in said end plate, openings in the flanges of each unit arranged alternately at opposite sides of said axis and angularly displaced from one another by more or less than 180° so as to provide in each annular chamber a divided passage of unequal length between successive openings, and means to 25 position said units in said casing and to secure same to said end wall.
10. In a device of the class described, a cylindrical casing having an inlet at one end and a centrally apertured end plate at its opposite end, a series of structural units within said casing, each comprising a plate having a plurality of annular concentric flanges projecting from one side thereof, the outer flange of each unit being spaced from said casing and the free edges of the flanges abutting the unflanged face of the adjacent unit to provide a series of annular concentric 30 chambers having a common axis, all of said units except the first being centrally apertured with the apertures formed thereby registering with each other and with the aperture in said end plate, openings in the flanges of each unit arranged alternately at opposite sides of said axis and angularly displaced from one another by more or less than 180° so as to provide in each annular chamber a divided passage of unequal length between successive openings, and means to 35 position said units in said casing and to secure same to said end wall.
11. In a device of the class described, a cylindrical casing having an inlet at one end and a centrally apertured end plate at its opposite end, a series of structural units within said casing, each comprising a plate having a plurality of annular concentric flanges projecting from one side thereof, the outer flange of each unit being spaced from said casing and the free edges of the flanges abutting the unflanged face of the adjacent unit to provide a series of annular concentric 40 chambers having a common axis, all of said units except the first being centrally apertured with the apertures formed thereby registering with each other and with the aperture in said end plate, openings in the flanges of each unit arranged alternately at opposite sides of said axis and angularly displaced from one another by more or less than 180° so as to provide in each annular chamber a divided passage of unequal length between successive openings, and means to 45 position said units in said casing and to secure same to said end wall.
12. In a device of the class described, a cylindrical casing having an inlet at one end and a centrally apertured end plate at its opposite end, a series of structural units within said casing, each comprising a plate having a plurality of annular concentric flanges projecting from one side thereof, the outer flange of each unit being spaced from said casing and the free edges of the flanges abutting the unflanged face of the adjacent unit to provide a series of annular concentric 50 chambers having a common axis, all of said units except the first being centrally apertured with the apertures formed thereby registering with each other and with the aperture in said end plate, openings in the flanges of each unit arranged alternately at opposite sides of said axis and angularly displaced from one another by more or less than 180° so as to provide in each annular chamber a divided passage of unequal length between successive openings, and means to 55 position said units in said casing and to secure same to said end wall.
13. In a device of the class described, a cylindrical casing having an inlet at one end and a centrally apertured end plate at its opposite end, a series of structural units within said casing, each comprising a plate having a plurality of annular concentric flanges projecting from one side thereof, the outer flange of each unit being spaced from said casing and the free edges of the flanges abutting the unflanged face of the adjacent unit to provide a series of annular concentric 60 chambers having a common axis, all of said units except the first being centrally apertured with the apertures formed thereby registering with each other and with the aperture in said end plate, openings in the flanges of each unit arranged alternately at opposite sides of said axis and angularly displaced from one another by more or less than 180° so as to provide in each annular chamber a divided passage of unequal length between successive openings, and means to 65 position said units in said casing and to secure same to said end wall.

In testimony whereof I have affixed my signature.

HIRAM PERCY MAXIM.

Certificate of Correction.

Patent No. 1,637,385.

Granted August 2, 1927, to

HIRAM PERCY MAXIM.

It is hereby certified that error appears in the printed specification of the above-numbered patent requiring correction as follows: Page 5, lines 12 and 13, claim 8, for the word "therethrough" read *therewith*; and that the said Letters Patent should be read with this correction therein that the same may conform to the record of the case in the Patent Office.

Signed and sealed this 6th day of September, A. D. 1927.

[SEAL.]

M. J. MOORE,
Acting Commissioner of Patents.
